VIBRATOR

William W. Garstang, Indianapolis, Ind., assignor to Electronic Laboratories, Incorporated, Indianapolis, Ind., a corporation of Indiana

Application July 17, 1940, Serial No. 345,999

4 Claims. (Cl. 200—90)

The present invention relates to improvements in vibrator switches and particularly to that type of vibrator switch wherein a reed is adapted to be rapidly vibrated through the instrumentality of an electromagnet for periodically interrupting an electric circuit.

This type of switch, in the commercial art, is frequently used for converting direct current into alternating current in a circuit wherein there is provided a transformer, the circuit of which is interrupted and reversed through the primary coil thereof at high frequency for causing the secondary to deliver to the load circuit an alternating current.

In certain types of these circuits, the frequency of vibration of the reed is necessarily so high that there is a great tendency on the part of the magnet for operating the reed to become abnormally hot due primarily to the fact that a poor magnetic path is provided for the magnetic flux of the electromagnet. As the result of this heating, considerable trouble is experienced, not only in the maintaining of the operation of the switch which will, under this extreme heating, disintegrate more rapidly but also, due to this extreme heating of the electromagnet, the frequency of the operation of the reed itself will vary. In certain circuits, a fluctuation or a variation in a frequency of the reed which accordingly will cause a fluctuation or variation in the frequency of the current eventually delivered, will materially affect the operation of the load imposed on the load circuit.

It is one of the objects of my invention to provide a vibrating reed switch which will stand up under severe conditions and which will not generate undue heat.

For the purpose of disclosing the invention, I have illustrated an embodiment thereof in the accompanying drawing, in which:

Fig. 1 is a side elevation of a vibrating reed switch embodying my invention;

Fig. 2 is a front elevation thereof.

In the embodiment illustrated, I preferably provide a frame comprising the two side members 1 and 2 which are formed of suitable metal and between which the various parts of the switch are adapted to be clamped. The switch proper comprises a vibrating reed 3 having a normal frequency corresponding to the frequency of the alternating current intended to be delivered. This reed has mounted thereon on opposite faces thereof two pairs of contacts, each pair being made up of oppositely mounted spring fingers 4 and 5 riveted or otherwise secured to the body

of the reed and carrying at their outer ends suitable contact points 6—6. Cooperating with the two pairs of contacts carried by the reed are two pairs of relatively stationary contacts, each pair comprising spring fingers 1 and 8 disposed on opposite sides of the reeds and carrying contacts 9—9 adapted to cooperate with the contacts 6—6. These sets of contacts are adapted for the opening and closing of the circuit to be controlled. 10 In addition to the above-mentioned sets of contacts, I preferably provide on the reed an additional contact 10 adapted to engage a relatively stationary contact 11 extending inwardly from the side 2. The reed and its associated relatively stationary contacts are clamped between the side members 1 and 2, with suitable spacers 12 disposed between the sides and the relatively stationary contacts and between the stationary contacts and the reed. There are certain of 15 these spacers, as for instance 13 and 13', formed of insulating material, so that the reed itself and the relatively stationary contacts will be insulated from one another and from the side walls 1 and 2 of the frame. The relatively stationary contact members 1 and 8 are in themselves flexible reeds which, however, are stiffened by back- 20 ing members 14 and 15 so that they will not vibrate and will be held in a relatively stationary position. These stiffening members are also 25 connected to additional braces 16 and 17, being connected thereto by set screws 18 extending through openings in the carrying reed 7 and 8. These set screws 18 provide means whereby 30 the distance between the contacts 6 and 9 may be very nicely adjusted.

For vibrating the reed 3, I provide an electromagnet, the winding 19 of which is wound upon and energizes a core 20. This core is formed of laminated sheets and is provided with a pair of outer poles 21 and 22 and a central pole 23. The winding 19 is actually wound upon the center pole 23 which is shorter than the two outer poles 21 and 22 and it is to be noted that the end 24 of the reed 3 lies between the two pole pieces 21 and 22 closely adjacent the same with its end 45 very closely adjacent the end of the center pole 23. The normal position of the end 24 of the reed, which comprises the armature of the electromagnet is offset or off-center with respect to the core of the winding so that when the winding is energized, there will be a tendency for the magnet to pull the end of the reed 4 toward the center against its natural or normal bias. The core 20 of the electromagnet is clamped between the side members 1 and 2 through suitable clamp-

ing bolts 25 which extend through the side members 1 and 2 and through the laminated core, suitable spacer sleeves 26 being provided for maintaining the laminated core in its position midway between the two side members 1 and 2.

In the structure illustrated, in operation, when circuit is closed through the energizing winding 19, the magnetic flux set up in the pole pieces and tending to pass through the armature end 24 of the spring will cause the reed 6 to move toward the center position between the two sides 1 and 2. This, of course, will separate the contacts 10 and 11 and as the contacts 10 and 11 are in the circuit of the winding 19, the circuit through the winding 19 will thus be broken, thereby deenergizing the electromagnet and permitting the reed under its own bias to swing back to again close the contacts 10 and 11. The reed is thus set in vibration and, due to the fact that an extremely good magnetic path is provided for the magnetic flux in the pole pieces 21 and 22 with a minimum of air gap between the armature 24 of the reed and the pole pieces, the switch can operate for long periods of time with a minimum of heating effect and with the maximum of power. This is extremely advantageous where the reed is operated at extremely high frequencies.

I claim as my invention:

1. In a vibrator reed switch, in combination, a pair of flat side plates, an electromagnet including a laminated core having a pair of legs forming pole pieces, means for supporting said electromagnet between said plates and at one end thereof with the laminae of said core disposed in planes parallel to the flat faces of said plates and with the active faces of said legs in a plane transverse to said flat side pieces, a reed, means for supporting one end of said reed between said side plates at the end thereof opposite said electromagnet with the free end of the reed extending toward said electromagnet, said free end supporting an armature with at least a portion thereof disposed between said legs and having its side edges closely adjacent the active faces of said pole pieces, said armature being normally disposed eccentric with respect to the magnetic force of said electromagnet and swingable transversely to the planes defined by the laminae of said electromagnet, contacts on said reed, relatively stationary contacts adapted to cooperate with said reed contacts, and means for supporting said stationary contacts between said plates.

2. In a vibrator switch, in combination, a pair of flat side plates, an electromagnet including a laminated substantially E-shaped core, means for supporting said electromagnet between said plates and at one end thereof with the laminae of said core disposed in planes parallel to the

flat faces of the side plates and with the open end of said core facing inwardly, the outer legs of said core being longer than the center stem and forming pole pieces having active faces located in a plane transverse to the plane of said plates, a vibrating reed supporting at its free end an armature with at least a portion thereof disposed between the outer legs of said electromagnet with its side edges closely adjacent the faces of said outer legs and with its top edge closely adjacent the bottom face of the center stem of said electromagnet, said armature being normally disposed eccentric with respect to the magnetic force of said electromagnet and swingable transversely to the planes defined by the laminae of said electromagnet, contacts mounted on said reed and relatively stationary contacts adapted to cooperate with said reed contacts, and means for supporting said reed and said relatively stationary contacts between said plates.

3. In a vibrator reed switch, in combination, a supporting frame, an electromagnet mounted at one end of said supporting frame including a laminated open ended magnetic core formed with parallel side legs and a top cross piece, a vibrating reed, means for supporting one end of said reed at the opposite end of said frame, said reed at its free end supporting an armature in a position with at least a portion thereof disposed between the extremities of said legs and normally eccentric to the lines of magnetic force of the pole pieces formed by said legs and swingable transversely to the planes defined by the laminae of said magnet, contacts carried by said reed, stationary contacts cooperating with said reed contacts, and means for supporting said stationary contacts in said frame.

4. In a vibrator switch, in combination, a supporting frame, an electromagnet mounted at one end of said frame and including a laminated open ended E-shaped magnet core, the outer legs of said magnetic core being longer than the center stem thereof, a vibrating reed, means for supporting one end of said reed at the opposite end of said frame, said reed at its free end supporting an armature in a position with at least a portion thereof disposed between the extremities of said side legs normally eccentric to the lines of magnetic force of the pole pieces of said magnet with its side edges closely adjacent the inner faces of said side legs and with its top edge closely adjacent the bottom edge of said center piece and swingable transversely to the planes defined by the laminae of said magnet contacts carried by said reed, stationary contacts cooperating with said reed contacts and means supporting said stationary contacts in said frame.

WILLIAM W. GARSTANG.
